CLAIM

The ornamental design for a specimen holder for microscope, as shown and described.

DESCRIPTION

FIG. 1 is a top perspective view of a specimen holder for microscope showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof, the left side elevational view being a mirror image thereof;

FIG. 8 is a front elevational view thereof in extended position; and,

FIG. 9 is a top plan view thereof.

FIG. 1

FIG. 2

FIG. 3

FIG. 4
